UNITED STATES PATENT OFFICE.

ANDREW WIRSING, OF MILWAUKEE, WISCONSIN.

HOISTING-BUCKET.

1,060,730.

Specification of Letters Patent.

Patented May 6, 1913.

Application filed December 12, 1912. Serial No. 736,260.

To all whom it may concern:

Be it known that I, ANDREW WIRSING, a citizen of the United States, and resident of Milwaukee, in the county of Milwaukee and State of Wisconsin, have invented certain new and useful Improvements in Hoisting-Buckets; and I do hereby declare that the following is a full, clear, and exact description thereof.

10 My invention consists in what is herein particularly set forth with reference to the accompanying drawings and pointed out in the claims of this specification, its object being to provide simple, economical, strong, 15 durable and efficient separable hoisting buckets of the "clam-shell" species, especial attention being directed to a peculiar suspension of the bucket-sections, the leverage of the same and the bucket-closing 20 mechanism.

Figure 1 of the drawings represents a sectional view of one of my improved hoisting buckets and is indicated by line 1-1 in the next described showing; Fig. 2, a similar view on the plane indicated by line 2-2 in Figs. 1 and 4, the bucket being open; Fig. 3, a like view of the open bucket indicated by line 3-3 in Figs. 2 and 4; Fig. 4, a plan view of the open bucket partly in horizontal 30 section on the plane indicated by line 4-4 in Fig. 3, and Fig. 5, a horizontal sectional view indicated by line 5-5 in Fig. 3.

Referring by numerals to the drawings, 6 indicates one and 7 the other of the pair of 35 segmental body-sections of an improved separable hoisting-bucket in accordance with my invention. The body-section 6 of the bucket is provided with a series of arms 8, and the body-section 7 of said bucket is 40 also provided with a series of arms 9, five arms being shown in one series and four arms in the other series. At their outer ends, the several arms are loose on a primary spindle 10 that extends through spacing sleeves 11 and 12 as well as shackle- 45 plates 13, each of these plates being intermediate of a pair of the sleeves and in connection with a suspended stop-chain 14. Loose on the spindle 10, between arms of 50 the body-sections of the bucket, is shown two pair of sheaves, those of one pair being indicated by the numerals 15, 15', and those of the other pair by the numerals 16, 16'. The spindle 10 and parts therewith are held 55 in place by nuts 17 run on the ends of said

spindle against outer arms of the body-sections of the bucket, or by other suitable means, said outer arms being riveted direct to the bucket-body sections adjacent to the inner corners of the same, and the other 60 arms of each series are likewise secured to angle-plates 18 similarly fastened on the curved portions of said bucket-body sections. Brace-plates 19 are shown riveted to angle-strips 20 likewise connected to the 65 outer arms of each bucket-body section and the next adjacent inner arms of the same.

A secondary spindle 21 extends through the inner arms of the bucket-body section 6, and another secondary spindle 22 extends 70 through the inner arms of the other bucket-body 7, these spindles being each held in place by nuts 23 run on the ends thereof against opposing arms of the series aforesaid, or by other suitable means. Loose on 75 the spindle 21 is shown a pair of sheaves 24, 24', and loose on the spindle 22 is shown another pair of sheaves 25, 25', all of these paired sheaves being shown as having a diameter greater than that of the sheaves on 80 the spindle 10. Each of the sheaves 24 and 25' is confined on its spindle between an arm 85 of a bucket-body section and a spacing-sleeve 26, while each of the sheaves 24' and 25 is confined on its spindle between a pair of said arms.

A head-frame is made up of vertically disposed paired channel bars 28, underlying angle-beams 29, vertically disposed paired flat-plates 30, horizontal flat plates 31 and 90 brackets 32, the several parts being riveted together. However the detail of said head-frame may be indefinitely varied. Link-bars 33 are connected at their ends to the paired channel-bars 28 of the head frame 95 and to paired brackets 34 with which the bucket-body sections are provided, each link-bar being interposed between a pair of said channel-bars and a pair of said brackets on pivot bolts 35, suitably held in place. 100

A spindle 36 is central of the head-piece parallel to the spindle 10 aforesaid, and said spindle 36 extends through the channel-bars 28 and plates 30 of said head-frame, it being held in place by nuts 37 run on the ends thereof in opposition to the adjacent channel-bars, or by other suitable means. The spindle 36 also extends through spacing-collars 38 and shackle-plates 39 intermediate 105 of such collars, these plates being connected 110

to the upper ends of the stop-chains 14 aforesaid.

Engaged by the spindle 36, central of the head-frame, is the hub of a yoke 40 constituting an equalizer in connection with bucket-closing cables 41, 42, opposing guide-sheaves 43, 44, loose on said spindle, and guard-rollers 45, 46, mounted in said frame to oppose said cables, these sheaves and 10 guard-rollers being arranged between plates 30 of the aforesaid frame. Sheaves 47 are loose on the spindle 36 between channel-bars of the head-frame, and hoisting-cables 48 are trained on the sheaves last specified, these 15 sheaves being shown as having a greater diameter than those 43, 44 on the same spindle.

With particular reference to Figs. 3 and 4, the cable 41, coupled to one end of the yoke 20 40, extends down under the sheave 15, then to the right over the sheave 25, then to the left under the sheave 24, then up under the sheave 15', and finally up between the sheave 44 and a guard-roller 46. The cable 42, 25 coupled to the other end of the yoke 40 extends down under the sheave 16, then to the left over the sheave 24', then to the right under the sheave 25', then up under the sheave 16', and finally up between the sheave 39 43 and a guard-roller 45. It will be understood that the cables 41 and 42 pull in opposite directions and that the strain thereon is equalized by the yoke 40 to which they are connected, in order to effect a uniform speed 35 of closing on the part of the bucket body sections, the hoisting of the bucket being effected by the cables 48. However it is practical, and within the scope of my invention, as herein claimed, to omit the hoisting cables 40 48, as well as one of the bucket-closing cables and sheaves upon which the same is trained, in which case the remaining bucket-closing cable serves also as a hoisting cable, but in either case provision is had for rapid closing 45 of the open bucket, the peculiar suspension of its body sections being such that powerful leverage is exerted thereon and a scooping action of the same obtained upon the material to be hoisted. The closed bucket being 50 hoisted to a desired altitude, slackening of the closing-cable or cables will result in an automatic opening of said bucket by gravity of its load to dump the same.

I claim:

55 1. A separable hoisting-bucket comprising a head-frame, body-sections and links connected to said frame and body sections; arms provided in connection with the body-sections, a spindle extending through all of the 60 arms, a pair of primary sheaves on the spindle, secondary sheaves carried in connection with arms of said body-sections, and a cable fast at one end in the head-frame from which it extends down under one of the primary 65 sheaves, thence over one of the sec-

ondary sheaves, thence back over another secondary sheave, thence up under the other primary sheave and finally up through the said head-frame.

2. A separable hoisting-bucket comprising 70 a head-frame, body-sections and links connected to said frame and body sections; arms provided in connection with the body-sections, a primary spindle extending through all of the arms, a pair of sheaves loose on 75 said spindle, secondary spindles each carried by arms of a body-section, a sheave loose on each secondary spindle, and a closing-cable fast at one end in the head-frame from which it extends down under one of the sheaves on 80 the primary spindle, thence in one direction over the sheave on one of the secondary spindles, thence back over the sheave on the other secondary spindle, thence up under the other sheave on the primary spindle and 85 finally up through said head-frame.

3. A separable hoisting-bucket comprising 90 a head-frame, body-sections and links connected to said frame and body-sections; arms provided in connection with the body-sections, a spindle extending through all of the arms, two pairs of primary sheaves loose on 95 said spindle, secondary sheaves in pairs carried in connection with arms of the body-sections, an equalizer-yoke oscillative in the head-frame, and a pair of closing-cables fast to opposite ends of the yoke from which they extend down oppositely under primary sheaves of the pairs aforesaid, thence over secondary sheaves, thence back over opposite 100 secondary sheaves, thence up under the other primary sheaves, and finally up through said head-frame.

4. A separable hoisting-bucket comprising 105 a head-frame, body-sections and links connected to said frame and body-sections; arms provided in connection with the body-sections, a spindle extending through all of the arms, a pair of primary sheaves on the spindle, secondary sheaves carried in connection with arms of said body-sections, a cable fast at one end in the head-frame from which it extends down under one of the primary sheaves, thence over one of the secondary sheaves, thence back over another secondary 115 sheave, thence up under the other primary sheave and finally up through the said head-frame, and hoisting-cable sheaves hung in the aforesaid head-frame.

5. A separable hoisting-bucket comprising 120 a head-frame, body-sections and links connected to said frame and body-sections; a spindle in the head-frame, arms in connection with the body-sections, another spindle extending through all of the arms, hoisting-cable sheaves, guide sheaves, an equalizing yoke and spacing-sleeves loose on the spindle first aforesaid; primary sheaves loose on the other of said spindles, secondary sheaves carried in connection with said arms of the 125

body-sections, and closing cables in connection with the ends of said yoke from which they extend down oppositely under primary sheaves, thence over secondary sheaves, back 5 over opposite secondary sheaves and finally up past the guide sheaves.

In testimony that I claim the foregoing I

have hereunto set my hand at Milwaukee in the county of Milwaukee and State of Wisconsin in the presence of two witnesses.

ANDREW WIRSING.
